SYSTEM FOR COOLING MINES AND OTHER CHAMBERS REQUIRING VENTILATION

Filed Feb. 25, 1924

UNITED STATES PATENT OFFICE.

WILLIS H. CARRIER, OF ESSEX FELLS, NEW JERSEY, ASSIGNOR TO CARRIER ENGINEERING CORPORATION, OF NEWARK, NEW JERSEY.

SYSTEM FOR COOLING MINES AND OTHER CHAMBERS REQUIRING VENTILATION.

Application filed February 25, 1924, Serial No. 695,045, and in Great Britain July 2, 1923.

A difficult problem is encountered in cooling deep mines when the depth of a mine reaches 5000 ft. or more. Not only are the 5 rock temperatures high, increasing about 1 degree for every 200 feet—but the air delivered down into the mine is heated up by compression. This natural heating due to adiabatic compression through increased barometric pressure would amount to nearly 10 30° for a depth of 5000' below the surface.

In addition to this, there is a large quantity 15 of moisture absorbed from water in the mine and from the rocks so that the degree of saturation is frequently as great, or even greater, than at the surface. This means a 20 great increase in moisture content and a correspondingly greater rise in the wet bulb temperature which indicates the total heat present in the air.

Large volumes of air are required for 25 ventilation of a deep mine because of the high rock temperatures which make it impossible to work such a mine without ample ventilation, and as the depth of the mine increases, the value of such ventilation becomes less and 30 less for the reasons just pointed out. In fact, at a depth of 5000' to 6000' the temperatures have reached the limit of human endurance.

Heretofore, attempts have been made to 35 reduce the temperatures in the lower workings by supplying thereto air cooled at the surface and removing the moisture to as low a point as possible. The effect of this has been to lower the temperature of the air somewhat in 40 the mine, but more particularly to lower its moisture content and has made it possible to work such a mine down to a level as low as 6000' even in warm climates. The effectiveness of such cooling is obviously largely lost by reason of the great transmission of heat to the air owing to the greater temperature difference, so that the cooling effect at the bottom 45 of the mine is in no way proportionate to the cooling effort at the surface.

As the depth of the workings are increased, the cooling at the surface becomes of less and 50 less value owing to the fact of the greater increase in temperature due to adiabatic compression and to the closer approximation of the air temperature to the rock temperature with increased length of the air-ways.

The obvious method, if it were practicable, 55 would be to cool the air, not at the surface, but in the workings near the point where the

air is to be used and, at the same time, to remove the moisture. One means of thus cooling the air would be either water at atmospheric temperature or artificially cooled water, or brine pumped down into the mine and then pumped back to the surface. The pressure on the pipes and cooling apparatus at such depths would become so excessive as to be impracticable in view of the enormous strength of the materials required to stand such pressures, and also would be very excessive in the consumption of power due to the cost of pumping the large quantities of cooling liquid required from the depth of the lower levels to the surface.

The proposition which I prefer is that of placing the refrigerating equipment in the mine, and which is made entirely practicable by the application of my improved system of centrifugal refrigeration operated at pressures below atmospheric pressure, thus avoiding all dangers attendant on such procedure. The problem then is still not fully solved because it is manifestly as impracticable to remove the heat from the condenser of the refrigerating apparatus by means of water at such depths as it would be to cool the air direct. However, I make use of the principle of refrigeration which enables me to transfer heat from a lower temperature level to a higher temperature level. This is accomplished in a manner coordinated with the existing ventilating system so as not to interfere with it and, in fact, so as to largely supplant the need of mechanical apparatus, such as fans, 90 for supplying the air for ventilation as will hereafter be explained.

This system comprises the application of a spray type of heat interchanger for cooling and dehumidifying the air entering the workings in which the air is brought into direct contact with a spray of artificially cooled water, however, a surface type of heat interchanger may be used if desired, although the effectiveness of heat transfer of the latter 100 would be less. On this account, as well as for the reason that the water vapor condensed will be returned directly to the circulating liquid, the spray system is preferably used.

Preferably, only a portion of the total air 105 entering the workings is directly cooled and dehumidified, and this is cooled to a lower temperature and lower moisture content than that of the air necessary in the workings, and the cooled portion of the air is then mixed 110

with the remaining portion of the air supplied to give an unsaturated mixture at the temperature desired.

The corresponding heat to be removed from 5 the condenser of the refrigerating equipment is taken care of through a spray type of heat interchanger placed in the outgoing air passage from the mine and through which the air passes in leaving the workings. In this 10 heat interchanger the circulating condenser water is cooled primarily by evaporation and the air leaves the interchanger at a condition of saturation at a slightly higher temperature than it leaves the workings. Thus the 15 heat removed from the air entering the workings is directly transferred to the air leaving the workings. The effect of the corresponding higher temperature in the outgoing air is to greatly decrease its density below what 20 it would be under natural ventilation. This produces a column of outgoing air which is much lighter than that of the incoming air, thus producing a strong up-draft which is either sufficient, or nearly sufficient, to cause 25 the flow of air necessary for ventilation without other means of air propulsion.

The system thus comprises two primary circuits of heat interchange; the first in which the water passes through the cooler of a 30 refrigerating machine and then through a heat interchanger, preferably of a spray type, which absorbs the sensible and latent heat from the moist air entering the working. In the second system of heat interchange, the 35 water passes through the condenser where the latent heat of the refrigerant is absorbed and then through a spray type of heat interchanger in which the condenser water is again cooled through a process of heat transfer and in contact with the current of the outgoing air. In both cases, means of water elimination are preferably provided to prevent 40 the water being carried beyond the points desired so that it may be retained in the respective systems. So then it is evident that there will be a continuous accumulation of water in the first system due to condensation from the air, and a continuous loss of water in the second system due to evaporation of water 45 into the air. The water accumulating in the first system can be used to advantage as make-up water for the second system so that only a small additional quantity of make-up water is required for the second system for the condenser water. The small amount of additional make-up water can be supplied from the mine water, or from the surface if necessary. It is evident that these two systems operate interdependently, merely re- 50 moving the heat from the air at the entrance point and transferring it and adding it to the air at the leaving point after the air has performed its function of cooling the mine workings and maintaining therein the desired 55 working temperature.

Another important feature of this invention is the method whereby a portion only of the air is cooled and dehumidified and then mixed with the remaining portion entering the workings in such a way as not to interfere 70 with the normal operation of the ventilating system and, at the same time, provide a thorough air mixture having a dew point, or saturation temperature, which is considerably lower than the dry bulb temperature of the 75 mixture. In other words, to provide a minimum wet bulb temperature, upon which the sense of bodily comfort depends, without an excessive lowering of the dry bulb temperature which would result in an excessive rate 80 of heat transfer from the mine to the air. This reduction of the wet bulb temperature, without an excessive reduction of the dry bulb temperature, is important because it avoids the danger of rock explosions which 85 occur in mines where air of too low a temperature is suddenly brought into contact with the rock, and also avoids undue chilling of the workers in the air-ways.

Preferably the cooling apparatus and the 90 fan for drawing the air through the same are placed in a chamber connected into a by-pass parallel with the main air-way. This draws a portion of the air through the apparatus and discharges it through a nozzle into an 95 aspirating tube forming a portion of the by-pass which causes an additional quantity of air to be drawn through the by-pass and discharged again into the main air-way after mixture with the cooled air. This avoids any 100 direct contact of the air at low temperatures with the rock, or with people passing through the main air-way.

This arrangement has great practical importance as it avoids the use of any deflectors 105 or air locks in the main air-way, therefore it interferes in no way with its normal use for the passage of the workers and the handling of the ore.

The accompanying drawing is a diagrammatic illustration of an apparatus embodying my invention, suitable for performing the method hereinbefore described.

In said drawing, 1 represents an air-way or chamber of the mine workings, and 2 and 3 indicate respectively the air inlet and exit shafts or passages which communicate with the mine or chamber so that air entering through the inlet passage will pass through the mine workings and escape through the 115 exit passage. 4 represents the bypass passage.

5 represents the heat interchanger or dehumidifier for dehumidifying and cooling the entering air, and 6 is a fan by which a portion of the entering air is caused to pass through the dehumidifier and is discharged through a nozzle 7 into the bypass passage 4. This dehumidifier is preferably located in a chamber 8 which communicates with the air-way 125 130

1 and the bypass 4, the dehumidifier being so arranged that the fan draws a portion only of the air from the inlet passage through the dehumidifier while another portion of the air can pass around or outside of the dehumidifier. The nozzle 7 and by-pass passage 4 form an aspirator or ejector whereby the discharge of the air through the nozzle 7 acts to draw a portion of the entering air around the dehumidifier and cause it to pass through the by-pass passage and thoroughly mix therein with the dehumidified and cooled air from the dehumidifier.

9 represents the heat interchanger or cooler for the condenser water of the refrigerating apparatus. This interchanger is arranged so that the air passing from the mine workings or air-way 1 to the exit passage 3 will flow through the interchanger 9.

10, 11 and 12 represent respectively the cooler or evaporator, the centrifugal compressor and the condenser of the refrigerating apparatus for cooling the water which is used in the dehumidifier 5 for cooling the incoming air. A suitable volatile refrigerating medium is employed in the refrigerating apparatus, the refrigerant being vaporized in the evaporator 10 by heat abstracted from the water, the refrigerant vapor being withdrawn from the evaporator, compressed and delivered by the compressor 11 to the condenser 12 in which the vaporized refrigerant is condensed, and the liquefied refrigerant being returned to the evaporator in the usual cycle of operations.

13 represents a water circulating pump which is connected by pipes 14, 15 and 16 with the dehumidifier 5 and the evaporator 10 in a closed water circulating system, so that the pump delivers the water, which is cooled in the evaporator 10, to the spray nozzles 17 of the dehumidifier and returns the spray water, which collects in the bottom of the dehumidifier, back to the evaporator. The water is thus recirculated in a closed circuit or system and used over and over, together with such additional water as is condensed from the air in the dehumidifier. The dehumidifier is provided in rear of the water spray nozzles with a water eliminator, preferably consisting of a multiplicity of spaced zig-zag vertical plates 18. The air, after passing through the water spray, flows through the zig-zag spaces between these eliminator plates, which act to separate the entrained free water from the air so that the air is discharged by the fan from the dehumidifier without entrained or free water.

Similarly, the condenser 12 of the refrigerating apparatus and the interchanger or cooler 9 for the condenser water are connected in a closed water circulating system by pipes 19, 20 and 21 and a pump 22 which delivers warm water from the condenser 12 to the spray nozzles 23 of the interchanger 9 and

returns the water collecting in the bottom of the latter back to the condenser. This interchanger 9 is also preferably provided with an eliminator 24, similar to the eliminator in the air dehumidifier, through which the air passes after contact with the water sprays for separating free or entrained water from the air. The evaporation of the spray water by the air leaving the mine workings through the cooler or interchanger 9 cools the water, and the cooled water is returned to the condenser 12 for condensing the refrigerating medium in the refrigerating apparatus.

The operation of the apparatus will be understood from the foregoing description of the method.

I claim as my invention:

1. The herein described method of cooling mines and other chambers comprising the following steps; cooling air by refrigeration in or near the mine or chamber to be cooled, supplying the air thus cooled to the mine or chamber for cooling the latter, and transferring the heat removed from said entering air to the air which leaves the mine or chamber after performing its function of cooling the mine or chamber, thereby decreasing the density of the leaving air and promoting the upward movement of the same from the mine or chamber.

2. A method of cooling mines and other chambers, which comprises cooling entering air by refrigeration in or near the chamber to be cooled, supplying the air thus cooled to the chamber for cooling the latter, and utilizing the outgoing air to cool the condensing medium used in the refrigeration, whereby the exit of the used air will be facilitated by its increase in temperature.

3. A method of cooling mines and other chambers, which comprises cooling the entering air by a cold circulating medium, refrigerating the cold medium, and transferring heat from the refrigerating operation to the outgoing air.

4. A method of cooling mines and other chambers having an air inlet and an air outlet at spaced points, which comprises refrigerating entering air to remove a portion of its moisture, conducting it to said chamber, subjecting the outgoing air to a continuous spray of a fluid medium, and using the latter as a cooling medium for the refrigerating operation, whereby the outgoing cool air in cooling the fluid medium and thus assisting in the refrigerating operation, will be heated thereby to facilitate its exit from the chamber.

5. The method of cooling mines and other chambers having an air inlet and an air outlet at spaced points, which comprises subjecting entering air to a spray of a cooling medium to cool the same and remove part of its moisture, admitting such treated air to the chamber, subjecting the outgoing air to a spray of a liquid to heat the same and cause a

cooling of the liquid, and refrigerating said cooling medium by utilizing for cooling purposes in connection therewith the liquid which is cooled by the outgoing air.

5 6. The method of cooling mines and other chambers having an air inlet and an air outlet at spaced points, which comprises refrigerating ingoing air to remove part of its moisture, admitting such refrigerated air to the 10 chamber, transferring the heat of refrigeration to the outgoing air by spraying a liquid used for cooling purposes in the refrigeration into the outgoing air, and making up the losses of evaporation in the last mentioned 15 liquid from the liquid removed from the entering air during its refrigeration.

7. The method of cooling mines and other chambers having an air inlet and an air outlet, which comprises subjecting ingoing air 20 to direct contact with a spray of a cold liquid to cool the same, removing the free moisture from the treated air, admitting the treated air to the chamber, refrigerating the liquid, and transferring heat of refrigeration to the 25 outgoing air.

8. The method of cooling mines and other chambers having an air inlet and an air outlet, which comprises subjecting entering air 30 to direct contact with a spray of a cold liquid to cool the air, eliminating the free moisture from the air, admitting the treated air to the chamber for passage therethrough, subjecting the outgoing air to direct contact with the spray of another liquid, removing the free 35 moisture from the air subjected to the last mentioned liquid, and cooling said cold liquid by utilizing the cooling effect of the outgoing air upon the second liquid.

9. The method of cooling mines and other 40 chambers having an air inlet and an air outlet, which comprises subjecting ingoing air at a point in said chambers, adjacent the base of the incoming air shaft to the cooling action of centrifugal refrigeration operating at 45 pressures below atmospheric pressure, and utilizing the cooling effect of the outgoing air as an aid in the refrigeration of the ingoing air.

10. The method of treating the air of 50 chambers of mines and the like, which comprises refrigerating at a point adjacent the entrance to the chamber to be treated, a portion only of the ingoing air to cool and dehumidify it to a lower temperature and a 55 lower moisture content than desired for the air used in said chamber, and then mixing this air with the remaining portion of the ingoing air.

11. The method of treating the air of 60 chambers of mines and the like, which comprises refrigerating at a point adjacent the entrance to the chamber to be treated, a portion only of the ingoing air to cool and dehumidify it to a lower temperature and a 65 lower moisture content than desired for the

air used in said chamber, then mixing this air with the remaining portion of the ingoing air, and utilizing the cooling effect of the outgoing air in cooling the ingoing air.

12. The method of treating air of chambers of mines and the like, which comprises 70 cooling a portion only of the ingoing air at a point adjacent the entrance to the chambers, and discharging it in a manner to produce an aspirating action which will cause a flow of 75 and mixture with additional ingoing uncooled air.

13. A method of treating the air of chambers of mines and the like, which comprises 80 cooling air entering said chamber at a point adjacent the entrance to the chamber by refrigeration, and utilizing the heat of the refrigeration to heat the outgoing air, whereby the outward movement of the air is facilitated 85 and the outgoing air is utilized in absorbing the heat of refrigeration.

14. A method of treating ventilating air of mine chambers and the like having inlet and outlet conduits communicating with the chamber at spaced points thereof, and 90 through which air is supplied to and removed from the chamber, said method comprising by-passing a quantity of the entering air at a point adjacent the entrance to the chamber, cooling part of this by-passed 95 air, mixing it with the remainder of the by-passed air, and commingling the by-passed air with the other entering air.

15. Apparatus for treating air of chambers of mines and the like, which comprises 100 a heat interchanger in the path of ingoing air, a second heat interchanger in the path of outgoing air at a point adjacent the entrance to the chamber, and refrigerating 105 means connected to both of said heat interchangers for cooling ingoing air by said first interchanger, and dissipating the heat generated by the operation of the refrigerating means to the outgoing air through said second interchanger.

16. Apparatus for treating air of mine chambers and the like, which comprises a heat interchanger, means for supplying a cooling medium to said heat interchanger, means for drawing a portion of the chamber air through said heat interchanger and discharging it in a manner to produce an aspirating action and draw and mix with it uncooled air.

17. Apparatus for treating the air of mine 120 chambers and the like, which comprises a liquid spray cooler and dehumidifier in a position to treat ingoing air, means for circulating a liquid through said cooler and dehumidifier to supply the spray therefor, an evaporator for cooling said liquid, means for compressing a refrigerating medium and supplying it to said evaporator for evaporation to cool said first liquid, a condenser for cooling the compressed refrigerating medium 125 130

- before it is admitted to said evaporator, and means including a heat interchanger in the path of outgoing air for cooling said condenser.
- 5 18. Apparatus for treating air of mine chambers and the like having a descending air inlet shaft and an ascending air outlet shaft, which comprises a heat interchanger adjacent the bottom of the inlet shaft for 10 cooling ingoing air, and refrigerating means for supplying cooling means to said heat interchanger, and a second heat interchanger adjacent the bottom of the air outlet shaft and connected to said refrigerating means 15 for utilizing the cooling effect of the outgoing air as an aid in the refrigeration of said cooling liquid.
19. Apparatus for treating air of mine chambers and the like, which comprises 20 means for subjecting ingoing air to a spray of a cold liquid to cool and dehumidify said air, removing the free moisture from said cooled air, means for spraying a liquid
- into outgoing air, including means for circulating the liquid forming the spray, means 25 for removing and returning to the last mentioned circulating liquid the free moisture in the outgoing air leaving said second spray, and refrigerating means for cooling the liquid supplied to the spray used in treating 30 the ingoing air and utilizing the cooling effect of the outgoing air upon the second liquid, whereby the free moisture removed from the cooled ingoing air may be used to supply the losses by evaporation of the second liquid 35 caused by the outgoing air.
20. Apparatus for treating ventilating air of mine chambers and the like, which comprises a cooling device, means for drawing a portion of the ingoing air through the cooling device and discharging it in a manner 40 to produce an aspirating action and draw and mix with it uncooled air, and means for conducting this mixture to the chamber.

WILLIS H. CARRIER.
